ABSTRACT OF THE DISCLOSURE

A rod feed trough is aligned with a washing or cleaning apparatus for conducting rods thereto to clean them prior to passing them through a thread forming machine. Adjacent the rod feed trough is a secondary magazine for supplying rods, one at a time, to the trough. Switch means are provided for actuating ejector means to eject the rods, one at a time, from the secondary magazine to the trough; for positioning dampening movement means adjacent the trough to inhibit undesired movement of the rod when it is in the trough and for moving the dampening means to accommodate reception of each rod into the trough.

As each rod is ejected into the trough from the secondary magazine, additional switch means actuates a spinning mechanism which engages the rod in the trough and imparts rotation thereto as well as longitudinal movement to move it into the washing apparatus.

Also, as each rod is ejected from the secondary magazine into the rod trough, switch means is actuated to eject a rod from a primary magazine into vice means which hold it while at least one end of the rod is chamfered.

After the rod is chamfered, the chamfering mechanism is first withdrawn from contact with the rod, the vice means opened, and the chamfered rod moved to the secondary magazine to replace a rod as one is ejected from the secondary magazine into the rod trough. When this occurs, switch means is actuated to place the ejector means on the primary magazine in position to thereafter eject a rod to the chamfer mechanism when another rod is ejected from the secondary magazine into the rod feed trough.

BACKGROUND OF THE INVENTION**Field of the invention**

This invention relates to a novel method and apparatus for the handling, preparing, and feeding of rods to a thread forming machine.

Description of the prior art

Prior to the present invention, applicant is familiar only with the practice of first washing the rods manually and then manually placing a rod in a trough, one at a time, and manually pushing it from the trough to the thread forming machine.

SUMMARY OF THE INVENTION

Briefly, the present invention relates to a method and apparatus for handling, preparing, and feeding rods, one at a time, to a thread forming machine including a primary ejection means for ejecting rods from a primary magazine to a chamfering means for chamfering at least one end of the rod, ejecting means for ejecting the chamfered rod to a means for moving the rod to a secondary magazine, secondary ejection means for ejecting the rod into a rod feed trough, and a spinner mechanism for spinning the rods toward and into a washing apparatus and then to the thread forming machine.

It is an object of the present invention to provide a new

2

method and apparatus for handling, preparing, and feeding clean rods to a thread forming machine.

Yet another object of the present invention is to provide a new method of automatically moving and preparing rods for threading with a thread forming machine including the steps of sequentially actuating a control timer which moves a spinner head to contact a rod in a rod trough that is spaced, but adjacent the thread forming machine, which spinner head spins the rod and also moves it toward the thread forming machine, there being a cleaning or washing apparatus through which the rod passes before entry into the thread forming machine, sequentially moving a dampening movement board to a position so that a rod may be ejected from a secondary magazine into the rod feed trough, moving the dampening board to a position adjacent the rod trough to prevent unwanted movement of the rod deposited in the rod feed trough, accommodating movement of the rods on the secondary magazine toward the rod feed trough when a rod is ejected into the rod trough, simultaneously ejecting a rod from a primary magazine as the rods move toward the feed trough to vice means which hold the rod while at least one end thereof is chamfered, and then moving the chamfered rod to the secondary magazine.

Yet still another object of the present invention is to provide an apparatus for handling and preparing rods for a thread forming machine including inclined primary magazine means for supporting a plurality of rods in side by side relation, primary ejection means for ejecting one rod at a time from the primary magazine, chamfering means for chamfering at least one end of the rod ejected from the primary magazine, chamfer ejecting means for ejecting the rod from said chamfering means, rod carrying means for moving the rod from the chamfer ejecting means, inclined secondary magazine means for receiving the chamfered rod from the rod carrying means and supporting the rod in side by side relation to other rods on the secondary magazine means, secondary ejection means for ejecting one rod at a time from the secondary magazine, a rod feed trough for receiving the rod ejected from the secondary magazine, a spinning mechanism for spinning and moving the rod forwardly in the feed trough toward the thread forming machine, and suitable means such as a solvent bath and brush means for cleaning each rod immediately before entry to the thread forming machine.

Still another object of the present invention is to provide a new and improved method and apparatus for preparing and handling rods for a thread forming machine wherein the operation of preparing and handling the rods is automatically performed by sequentially actuated and co-ordinated means.

Still another object of the present invention is to provide a new and improved method and apparatus for preparing and handling rods for a thread forming machine wherein the operation of preparing and handling the rods is automatically performed by sequentially actuated, co-ordinated valve means in co-operation with other apparatus.

60 BRIEF DESCRIPTION OF THE DRAWINGS

FIG. 1 is a top plan view of the preferred form of the invention for handling, preparing, and feeding rods to a threading machine; it shows the relationship of the primary magazine to the chamfering arrangement, secondary magazine and rod feed trough;

FIG. 2 is a front end view taken along line 2—2 of FIG. 1 illustrating in greater detail a rod feed trough, a movement dampening means, a spinner head mechanism, and washing apparatus of the present invention;

FIG. 3 is a sectional view, partly in elevation, taken along line 3—3 of FIG. 1 illustrating the relationship of

primary magazine means, chamfer mechanism, conveying means, secondary magazine means, and a form of rod feed trough of the present invention for handling, preparing, and feeding rods to a thread forming machine;

FIG. 4 is a sectional view, partly in elevation, taken along line 4—4 of FIG. 1 of the cleaning or washing means of the present invention;

FIG. 5 is a sectional view, partly in elevation, taken along line 5—5 of FIG. 4 illustrating in greater detail a form of the cleaning and washing apparatus of the present invention;

FIG. 6 is an end view taken along line 6—6 of FIG. 5 illustrating a drive assembly for driving the brushes in the cleaning or washing apparatus of the present invention;

FIG. 7 is a perspective view, partly in section, illustrating further details of some of the parts of the washing and cleaning apparatus of the present invention;

FIG. 8 is a sectional view, partly in section, taken along line 8—8 of FIG. 5 illustrating one form of an arrangement of a switch means and its relationship to a rod traveling through the washing or cleaning means;

FIG. 9 is a sectional view, partly in elevation, taken along line 9—9 of FIG. 1 illustrating the relationship of the rod feed trough, the movement dampening means, and a portion of the secondary magazine switching means of the present invention and showing the rod feed trough support means partially phantommed in;

FIG. 10 is a sectional view, partly in section, taken along line 10—10 of FIG. 1 and 10—10 of FIG. 12 illustrating some details of the spinner head mechanism of the present invention;

FIG. 11 is a sectional view, partly in elevation, taken along line 11—11 of FIG. 1 illustrating the relationship of the spinner head mechanism and the support framework on which it is carried adjacent the end of the rod feed trough;

FIG. 11A is a sectional view, partly in section, taken along line 11A—11A of FIG. 11 illustrating the relationship of a roller carrier block to adjustment means therefor;

FIG. 11B is a detail view of one portion of the invention;

FIG. 12 is a sectional view, partly in elevation, taken along line 12—12 of FIG. 1 illustrating the position of the spinner head mechanism when engaged with a rod that is positioned between the spinner head mechanism and the backup rollers;

FIG. 13 is a sectional view, partly in elevation, taken along line 13—13 of FIG. 1 illustrating the relationship of the secondary ejection means to the secondary magazine when the ejector means is in retracted position and ready to move up and eject a rod into the rod feed trough, and also illustrates diagrammatically the relationship of the rod movement dampening means to the rollers on the rod feed trough when the secondary ejector means is in the position shown;

FIG. 14 is a view similar to FIG. 13 but showing the ejector means actuated to eject a rod from the secondary magazine and again diagrammatically illustrates the relationship of the movement dampening means to the rollers on the rod feed trough when a rod is being ejected thereon from the secondary magazine;

FIG. 15 is a sectional view, partly in elevation, taken along line 15—15 of FIG. 1 illustrating in detail one of the rod support means used in conjunction with the chamfering mechanism and a rod elevator means adjacent the secondary magazine for conveying rods from the chamfer mechanism to the secondary magazine;

FIG. 15A is a sectional view, partly in elevation, on the line 15A—15A of FIG. 15 illustrating diagrammatically the preferred position of the rod support means and rod when engaged by the vice means for chamfering at least one end of the rod;

FIG. 16 is a schematic diagrammatic representation of 75

the main portion of the electrical and hydraulic system of the present invention;

FIG. 17 is a schematic representation of the electrical and hydraulic system used in conjunction with the chamfer mechanism and vice means which hold each rod as it is chamfered;

FIG. 18 is a side elevation taken along line 18—18 of FIG. 1 illustrating the relationship of the primary magazine to the chamfering mechanism and one of the gripping or vice means used in conjunction with the chamfer mechanism of the present invention;

FIG. 19 is a view taken along line 19—19 of FIG. 18 illustrating in further detail the relationship of the primary magazine, primary ejection means, gripping or vice means of the chamfer mechanism, and chamfer means of the present invention as a rod is ejected from the primary magazine;

FIG. 20 is a view similar to FIG. 19 but illustrating the position of each rod in the gripping or vice means of the present invention and ready to be engaged by the chamfering mechanism for chamfering of the rod;

FIG. 21 is a sectional view, partly in elevation, taken along line 21—21 of FIG. 20 illustrating the relationship of the chamfer mechanism as it moves in to chamfer an end of the rod which is engaged in the gripping means of the present invention;

FIG. 21A is a view along the line 21A—21A of FIG. 20 and shows a means for adjusting the framework of each vice means;

FIG. 22 is a top view of the gripping or vice means and ejector means associated therewith with a covering plate removed;

FIG. 23 is a partial sectional view taken along line 23—23 of FIG. 22 illustrating the relationship of the ejector means to the gripping means when the gripping means is in open position;

FIG. 24 is a partial view of the chamfer head blades engaged with a rod, and means mounted with the chamfer means of the present invention and shown as engaged with the end of the rod for actuating a switch means;

FIG. 25 is a view taken along line 25—25 of FIG. 1 illustrating wheel and track means for adjusting the gripping means of the present invention to accommodate rods of varying length;

FIG. 26 is a perspective view of the vice means showing it in open position and the ejector means associated therewith in elevated position;

FIG. 27 is a sectional view in perspective on the line 27—27 of FIG. 1 and illustrating suitable means for adjusting one end or headboard of the primary magazine means to align it so that the rods will be aligned endwise properly when ejected from the secondary magazine means into the rod feed trough; and

FIG. 28 is a partial view illustrating in greater detail the adjustable support means for the rod feed trough.

DESCRIPTION OF THE PREFERRED EMBODIMENT

Attention is directed to FIGS. 1, 2, and 3 wherein the apparatus for preparing, handling, and feeding rods to a thread forming machine is generally designated by the numeral 10. The invention 10 generally comprises a rod rack designated generally at 11, a primary magazine designated generally at 12, a chamfering mechanism designated generally at 13, elevator assemblies designated generally at 14, a secondary magazine designated generally at 15, a rod feed trough assembly designated generally at 16, a spinner head mechanism designated generally at 17, and a washing or cleaning means designated generally at 18. As illustrated in FIGS. 1 and 2, a thread forming machine of well-known construction is illustrated by dotted lines at 20 in FIG. 1, and by partial view, at 20 in FIG. 2. The thread forming means 20 is adjacent the cleaning means 18 and receives cleaned rods therefrom and performs the function of pressing threads on the outer sur-

face of rods inserted at the entrance 21, using dies for formation of the threads on the rods.

WASHING OR CLEANING MEANS

The elements and parts of the washing or cleaning means 18 are illustrated in greater detail in FIGS. 4, 5, 6, 7, and 8. The washing means 18 includes a suitable enclosure 25 formed of metal or other suitable material with a window 26 of glass or plastic positioned in an upper portion or wall 27 of the enclosure 25 by removable clamps 28 to enable a viewer to peer into the enclosure 25 to view the operation of a portion of the cleaning or washing means 18.

As illustrated in FIG. 4, which is a view taken along line 4-4 of FIG. 1, the enclosure 25 also includes end walls 29 and 30, sidewalls 32 and 33, and a bottom wall 31 which are joined with the end walls and upper portion in any suitable manner to form the enclosure 25. It may be connected together in any suitable manner so that portions thereof may be removed for access to the interior.

A motor 36 is mounted in any suitable position such as on the upper surface of the bottom wall 31. The shaft 36a of the motor is connected to operate pump 37. The intake or suction side of pump 37 is communicated with a liquid washing or cleaning solvent bath container 34 by means of the tube 33 which extends above the bottom of container 34 to inhibit sludge and debris removed from the rods from being recirculated. A clean-out plug 34a is provided to clean out container 34 when necessary. The container 34 is formed adjacent the bottom of the enclosure by means of the partition 35 which extends across and above the bottom wall 31 in enclosure 25 and which has upwardly extending portions 34a and 34b secured by any suitable means such as welding to end walls 29 and 30, respectively, and by means of portions 34c connected with side walls 32 and 33 of the enclosure. The portion 34c connected with sidewall 32 is visible in FIG. 4 of the drawings, and the portion 34c joined by suitable means to wall 33 is visible in FIG. 5. The partition 35 may be shaped as shown in FIG. 4 to provide a sloping drain surface 35a to convey solvent liquid from opening 47 in slanted floor 41 beneath stainless steel wire brushes 45 and 46 through tube 48 to the liquid reservoir O.

The discharge 38a of pump 37 is communicated through tube 39 which passes through opening 40 in end wall 30. The tube 38 may be bent as shown at 38b and is provided with a suitably shaped discharge nozzle 34c to spray liquid solvent on the brushes 45 and 46 and rod R and clean them. The brushes 45 and 46 are shown as engaged with rotating rod R and serve to remove any substance thereon and the washing liquid in turn cleans the brushes and may aid in removal of dirt or other substances from the rod R as it passes through the washing machine 18.

The washing liquid and entrained substances fall to floor 41 positioned beneath the brushes 45 and 46 and flow through opening 47 and tube 48 to liquid reservoir O. Any suitable liquid may be used to accomplish the desired result, and a suitable solvent serves the purpose quite well.

The brushes 45 and 46 are enclosed within enclosure 25 by the spaced walls 41a connected to floor 41. The end walls 41c are joined with walls 41a and extend upwardly to the top 41b which joins the walls 41a and 41c together to form an enclosure within enclosure 25 to separate brushes 45 and 46 from the other components in the enclosure 25.

The walls 41a have an opening 41d therein through which rod R passes. Secured to wall 33 around opening 33a is an arrangement 33b having jets for jetting air on the rod R to clean it of solvent and other foreign matter before the rod R passes to the thread rolling machine. This also helps to keep the solvent in the washing apparatus. The air source is not shown, nor is its connec-

tion with 33b shown, as it may be made in any suitable manner.

As will be described in greater detail, the rod is spinning and moving longitudinally as it passes through openings 32a and 33a in sidewalls 32 and 33 of the enclosure 25 and between brushes 45 and 46.

It is important for the rod R to be spinning as it enters the thread forming machine 20 because such spinning action enables the rod R to enter the gripping action of the dies of the thread forming machine without preventing damage to the dies.

The brushes 45 and 46 are adjustable relative to each other so that various diameters of rods can be accommodated by the invention 10. The brushes 45 and 46 are mounted on members 50 and 51 (FIG. 4), which members 50 and 51 are in turn secured to rotatable shafts 52 and 53, respectively, by any suitable means such as nuts 54 (FIG. 5) engaged with the threaded ends of each shaft.

As illustrated in FIGS. 5 and 7 in greater detail, each shaft 52 and 53 extends through a pair of shaft retainer members 56, which have ball bearings 57 therein to accommodate rotation of each shaft 52 and 53. Each of the pair of retainer members 56 is mounted in the enclosure 25 on adjustable slides 60 at each end 60a and 60b thereof. As illustrated in FIG. 5, the shafts 52 and 53 extend outwardly through openings 32b in the wall 32. Sprockets 62 and 63 are secured to the ends of the shafts 52 and 53, respectively.

Each of the travelling or adjustable slides 60 is supported by support rods 65 and 66 which extend through openings 60c in each of the slides. It should be noted that each of the traveling slides 60 is adapted to slide on the support rods 65 and 66. The rods 65 and 66 are mounted by suitable means such as set screws at one end 67 in openings through a support block 69 and are mounted at their other end 70 in openings through a similar support block 71 (FIG. 5). The blocks 69 and 71 are fixedly mounted in enclosure 25 by any suitable means. The rods 65 and 66 also extend through and are carried by a center support member generally designated at 72 in FIGS. 5 and 8.

Referring to FIGS. 5 and 7, a pair of rods 85 is provided with external threads 85a thereon. Each rod 85 is engaged with its respective slide 60 in an opening and has an enlarged end retained within such opening (not shown) by split plate 87 and screws 87a. The rods are threaded at 89a through the blocks 69 and 71, and rotation of the rods moves slides 60 along the rods 65 and 66. The rods 85 extend through front and rear walls 29 and 30, respectively, of enclosure 25, and rotate freely in an opening in the supporting front and rear walls. The rods 85 extend outwardly of the enclosure 25 and are connected at their ends 87 with hand wheels 88 for rotation of each rod or shaft 85.

With this arrangement, each of the traveling slides 60 is independently adjustable so that the space 90 (FIG. 4) between the brushes 45 and 46 is adjustable as desired for various sizes of rods R.

As illustrated in FIG. 6, a continuous link chain 91 contacts each sprocket 62 and 63 to thereby impart rotation to the shafts 52 and 53, respectively, which in turn imparts rotation to the brushes 45 and 46, respectively. A motor represented at 92 may be secured adjacent the enclosure 25 as represented at 93 and includes a drive shaft 95 for imparting rotation to the sprocket 96 carried thereby. The chain 91 is engaged with sprockets 96, 62, 63, and 99, and the motor imparts movement to continuous chain 91 such as, for example, in the direction of the arrow 96a imparts rotation to the sprocket 63 and brush 46 in the direction of the arrow 97 and rotation to the sprocket 62 and brush 45 in the direction of the arrow 98 to continuously engage the rod R and continuously clean it as the rod R is spinning and moving through the washing or cleaning apparatus 18.

As further illustrated in FIG. 6, a guide member 100 is mounted by any suitable means such as bolts or welding beneath and at an angle with respect to sprockets 62 and 63 to some part of the frame, and slidably fitting in guide 100 is slide 101. Attached adjacent one end of slide member 101 is the sprocket 99. The sprocket 99 is mounted on 101 by any suitable bearing means to permit sprocket 99 to rotate relative to its support, which is slide member 101. Thus, member 101 slidably fits in guide 100. The other end 101a of slidable member 101 is secured to one end 102a of spring 102, and the other end 102b of spring 102 is fixedly secured to some fixed support.

This arrangement permits sprocket 99 to move when blocks 60 are moved to adjust the space 90 between rollers 45 and 46 to accommodate different size rods.

The teeth 99a on sprocket 99 are representative of the teeth on the other sprockets.

The central support member 72 is shown in greater detail in FIG. 8. It includes spaced block members 73 and 74 having an opening through each. The sleeve 79 is secured to each block by set screws 75, and the end of the sleeve extends out opening 32a in sidewall 32 as illustrated. An inner sleeve 76 which is slightly larger than the rod R to be threaded is received within sleeve 79 and retained therein by bolts 78 which fit through flange 77 and into member 73. The aligned openings 81 and 82 in each sleeve 79 and 76, respectively, communicate with the bore 80 of inner sleeve 76 and wheel plunger 83 rides on the surface of the rod R as a rod moves through the machine. When the end of the rod R passes out from under the wheel 83, the wheel 83 drops by gravity to disconnect or open limit switch 104, thus holding the board in the position shown in FIG. 14.

The inner sleeve 76 can be changed to accommodate the particular size rod R being threaded.

The wheel plunger means 83 located in the washing or cleaning enclosure 25 is connected to actuate the switch means 104 as designated in FIG. 5. The wheel 83 is secured to a lever or arm 103 which in turn is pivotally supported and is secured to lever 831 (FIG. 16) for tripping limit switch means 104. The function and operation of the switch limit means 84 located in the washing or cleaning means will be brought out and explained in more detail hereinbelow with regard to FIG. 16.

ROD FEED TROUGH

As illustrated in FIGS. 2, 3, and 9, the rod feed trough generally designated at 16 includes a supporting base designated at 150, which base 150 includes a plurality of horizontally spaced, vertically extending support plates 151, each of which is provided at its lower end with a foot member 153 (FIG. 3). The upwardly extending edges of each plate 151 may be provided with a reinforcing as shown at 151a and 152.

The rod feed trough 16 of the present invention may be formed of a conventional channel designated at 160 which includes a flat base 161 with upstanding extending edges 162 and 163.

A plurality of roller support members 164 and 165 is mounted on the edges 163 and 162, respectively, in horizontally spaced, offset, notched openings in the edges as illustrated in FIGS. 9 and 28. Support rollers 166 and 167 having suitable bearings are mounted in the supports 164 and 165 and support a rod R positioned in the trough as shown in FIGS. 3 and 9.

The rod R positioned on rollers 166 and 167 in the feed trough 160 has been ejected from the secondary magazine 15 (FIGS. 1 and 3) into the trough 160 so that the spinning head mechanism 17 may engage and spin the rod R forwardly for entry into the washing apparatus 18 and then into thread forming machine 20. It can, of course, be appreciated that when the rod R is ejected from the secondary magazine 15 and deposited on the rollers 166 and 167 in the feed trough 160, the rod R may have a

tendency to whip and move about in unwanted directions when engaged by the spinning head mechanism 17. A movement dampening means 170 is provided to prevent such movement and includes a movement dampening board 171 which extends the longitudinal extent of the feed trough 160, and when rod R is in the trough, the board 171 is immediately above, but spaced from, the rod R as illustrated in FIGS. 3 and 9, thus preventing the rod R from moving in undesired directions and to insure that the rod R does not jump out the feed 160. A plurality of 90° angle arms 172 having a 90° bend at 173 is secured at one end 174 by suitable nut and bolt means 175 to the board 171 at spaced intervals as shown in FIG. 2.

The angle arms 172 are provided adjacent their other ends 176 with a collar 177 (FIG. 2) secured to pole 180 rotatably carried in plates 151 by any suitable means so that when the pole 180 rotates as will be described, the collars 177, arms 172, and board 171 secured thereto pivot about pole 180. The edge 151a of each plate 151 is shaped to provide an opening 188 to receive the longitudinally extending movement dampening pole 180.

A plurality of stop arms 182 spaced along feed trough 160 is secured at one end by any suitable bolt means 183 to edge 163 of the trough 160 and extends upwardly and is inclined outwardly at an angle as illustrated in FIG. 9. These prevent the rods R from bouncing out of the rollers in the feed trough when ejected from the secondary magazine. A cushion or stop means such as bolt 184 is positioned adjacent the upper end of each of the arms 182 by securing the nut 185 adjacent the upper end of 182 and aligned with an opening so that bolt 184 may be threadedly engaged therewith. As the board 171 is rotated arcuately outwardly from its position over the feed trough 160, it contacts the cushion bolt 184 to prevent and stop further movement.

A depending arm 187 has at one end a collar 188a secured by suitable means such as set screws to the pole 180 so that when the pole 180 is rotated, the arm 187 also rotates. The arm 187 is provided with openings 189 along its longitudinal length, one of which openings 189 is adapted to receive a nut and bolt means represented at 190 secured to an adjustable sleeve 191 held in position by lock nuts 191a, at each end thereof on rod 192, only one lock nut being visible. A piston rod 192 receives the adjustable sleeve 191, which shaft 192 is secured with the end of a piston (not shown) in a hydraulic cylinder 193.

A pivotal bracket member 194 extends outwardly from an end 193a of the hydraulic cylinder 193, and is secured by suitable nut and bolt means 195 to a bracket 196 secured with leg member 151 such that the cylinder 193 can pivot about the nut and bolt means 195 when the piston rod 192 moves in and out the cylinder 193.

As the rod R passes through the washing or cleaning means 18, the switch means 104 (FIG. 5) and more specifically the wheel plunger 83 rides along the top surface of the rod as illustrated in FIG. 8. When the end of the rod R passes the wheel plunger 83, it drops downwardly further into the opening 80 to actuate the limit switch means 104 which in turn effects movement of the dampening means 170.

When wheel plunger 83 moves downwardly at the end of a rod R and actuates the movement dampening means 170, as will be described in greater detail hereinafter, the arm 187 moves inwardly in the direction of the arrow 200, and a bracket 201 secured by any suitable means to the lower end of the arm 187 and bolt 202 connected with the bracket 201 by suitable nut means 203 moves inwardly to enable the head 204 of bolt 202 to contact a compressible plunger head 205 of a secondary magazine switch means 206. This causes another rod R to be ejected onto the feed trough from the secondary magazine, as will be described. The secondary magazine switch means is mounted by suitable nut and bolt means 207 and bracket means 208 to the end 193b of the movement dampening means hydraulic cylinder 193.

SPINNING HEAD MECHANISM

Referring to FIGS. 10, 11, 11A, and 12 of the present invention 10, the spinning head mechanism is generally designated by the numeral 17 as in FIGS. 1 and 2. As rods R are ejected from the secondary magazine generally designated at 15 by actuation of the secondary magazine switch means 206 (FIG. 9), the ejected rod R (FIG. 11) rolls onto support member 225 and onto an extension support member 226 mounted with a depending arm 225a of support member 225. Support member 225 is mounted and secured by any suitable means such as welding to the upper end of supporting rack leg 227 which is substantially parallel to leg 152 (FIG. 3) of the rod feed trough 16.

The spinning mechanism 17 of the present invention 10 is positioned between washing or cleaning means 18 and the rod feed trough 16 and is designed to impart rotation and longitudinal movement to the rod R so that the rod R will be fed into the thread forming machine 20 and rotated simultaneously to avoid damage to the thread forming dies.

A pair of spaced I beams 228 and 229 is secured with leg members 227. The I beams 228 and 229 extend outwardly transverse to leg members 227. The other end of I beams 228 and 229 as illustrated with the end 228a of I beam 228 is secured to a cross support member (not shown) which in turn supports the cylinder head 230a of a spinning head hydraulic cylinder 230 by any suitable means such as by bolts. Hydraulic cylinder 230 is double acting with the end 230b connected to tubing 231 for communication of fluid to the end 230b through spring loaded valve V. Tubing 232 extends from valve V and communicates with tubing 233 to the other end 230a of cylinder 230.

A piston rod 235 is secured with the piston (not shown) in the cylinder 230 and extends outwardly therefrom to be threadedly connected as illustrated at 236 with a vertically extending, horizontally movable plate member 237 which extends downwardly between the I beams 228 and 229, as illustrated in FIG. 10. A spinning head motor SM is carried by suitable means such as bolts (not shown) on gear reduction box 241 and is connected through the motor shaft 240 to rotate the gears in the gear reduction box 241. The gear reduction box 241 is in turn connected with a shaft 242 for mounting a spinning wheel or spinning head 245 on one end thereof. The spinning head 245 is constructed of a suitable nonabrasive material which resists wear but which material is suitable for spinning the rod R and moving it forwardly about a rotational axis which will be discussed in more detail hereinbelow.

Gear reduction box 241 is integrally formed with the mounting block 246 which in turn is secured by any suitable means such as bolts to block member 247. A pivotal block 248 is secured by any suitable means such as bolts to the block 247. The nuts and bolts (not shown) which connect 247 and 248 together fit in slots (not shown) in 247 so that 247 and 248 may be vertically adjusted relative to each other. This enables the motor SM and gear box 241 and spinning head 245 to be adjusted so that spinning head 245 can be centered on or relative to the rod R. Pivotal block 248 is secured to movable block 237 at one end 248a by suitable nut and bolt means designated at 249.

An arcuate slot 250 (FIG. 10) in movable block 237 receives a bolt shaft 251 which is secured at one end with the pivotal block 248 and which extends outwardly through the slot 250 to receive a nut 252 to retain the block 248 immediately adjacent the movable block member 237. A threaded arm 255 is threadedly secured at one end through an opening in the bolt shaft 251 and is secured at the other end to a knob 256. A support member 257 is secured along the edge 237a of the movable block member 237 to receive an enlarged lip 258 of the knob

256. Thus, the support member 257 permits the knob 256 to be rotated therein and thereby positions the pivotal block 248 at any desired angle defined by the arcuate slot 250 such that the angle of the spinning head 245 may be adjusted relative to the rod R. The shaft 251 can be inserted in other suitable holes illustrated at 260 in block 248. This permits the head 245 to engage the rod R at a desired angle depending upon the size rod.

A cross support member (not shown) extends between 10 and is secured to the I beams 228 and 229. An additional stationary cross support 265 is fixedly secured on top thereof as illustrated in FIG. 10, and guides or rods 270 and 271 are secured thereto by any suitable means such as set screws (not shown) extending through 15 265 and engaging 270 and 271 where they extend through holes 270a and 271a in 265.

The plate 237 is secured by screws 266a (FIG. 12) to a second cross member 266 which is below the members 247 and 248. The support bars 270 and 271, each of 20 which is positioned adjacent one side of the movable plate 237 and parallel to I beams 228 and 229, respectively, as shown in FIG. 10, extends through openings in member 266. One end 272 of each of the support bars 270 and 271 is received within and secured to the bar 25 and the other end 273 of each of the support bars is received by and secured to stationary block member 280 at the other end of 228 and 229 which is identical to member 265. The block member 266 is adapted to 30 slide along the bars 270 and 271 for movement of the movable plate 237 inwardly toward the rod R when the hydraulic cylinder 230 moves plate 237, which will be explained hereinbelow. It should be noted that block 280 is positioned on the opposite end of I beams 228 and 229 and that the support bars 270 and 271 extend 35 through the block member 280 adjacent the ends 273 thereof.

A threaded limit movement bar 285 is threadedly connected to the lower end of the end of the cylinder head 40 230a of the cylinder 230 and loosely extends through an opening 286 (FIG. 11) in the movable plates 237. The bar 285 is provided with nut and lock nut means 287 and 288, respectively, which are adjustable along the longitudinal length of the bar 285 to serve as a stop or limit of the spinning head mechanism by contact 45 with plate 237.

A limit switch arm 290 connected with limit switch 291 on the end thereof is connected or mounted on the block 265 for a purpose to be brought out hereinafter. The bolt 249 is hollow and threadedly secured therein and 50 extending therefrom is rod 293 for contact with switch arm 290 when plate 237 is retracted to cut off spinning motor SM and for starting motor SM when cylinder rod 235 moves plate 237 toward rod R in the feed trough so that 293 disengages from arm 290.

55 A pair of adjustable back-up rollers 298 and 299 is positioned vertically relative to each other, with the roller 298 illustrated as being positioned above the vertical roller 299. The rollers 298 and 299 are secured to a carrying block 300 by suitable shafts 301. The carrying block 60 300 is provided with openings (not shown) in the lower portion thereof for slidably receiving the support bars 270 and 271 and is adjustable along the length of the bars 270 and 271. An arm 305 is threadedly engaged with the cylinder head 230a of the cylinder 230 and is provided with 65 a hand wheel or knob 306 for rotation of the arm 305. As illustrated in FIG. 11A, the other end 305a of the arm 305 extends loosely through an opening 380a in the block 280 and is secured by a suitable pin means 307 to a curved lever arm 308 having a slot 309 therein for 70 receipt of the pin 307. The other end of the arm 308 is secured by a pivotal pin 310 to a stationary extended arm 311. The arm 311 is supported by member 280. The pin 307 extends upwardly from a sleeve 307a which is supported on a reduced portion 305b or rod 305. A nut 75 305c locks sleeve in place and permits rod 305 to rotate

relative thereto when the wheel 306 is turned. The pin slides in slot 309 when the rod or shaft is rotated.

An arm 315 is engaged in an opening in one end with block 300 and is held in position by lock plate 315a (FIG. 11a) secured to 300 by bolts. The arm extends rearwardly from block 300 through an opening 280b in member 280, and the other end 315a of the arm 315 is provided with an opening 316 for receipt of the curved lever arm as illustrated in FIG. 11A. If it is desired to adjust the block 300 and rollers 298 and 299 relative to the rod R, the knob 306 is manually rotated which thereby rotates and moves the arm 305 and moves lever arm 308. As the lever arm 308 is moved, it engages against the end of the opening 316 in rod 315 and thereby moves the arm 315 and block 300 in the desired direction with the block sliding 15 along the support bars 270 and 271.

As illustrated in FIG. 11, when the rod R rolls off member 226, it contacts a spinning head switching assembly means designated generally at 320 by engaging and depressing a spring loaded lever 321 which pivots about the pin 322 secured with block 300. Such downward movement depresses a spring 323 mounted on microswitch 324 to enable the lever 321 to depress plunger 321a of microswitch 324 and to actuate a timer 330 (FIG. 16), which in turn actuates a solenoid in the timer to actuate solenoid 810 (FIG. 16) connected to valve V. When this occurs, the solenoid 810 remains energized to hold valve V open until the preset timing period in the timer runs out. When solenoid 810 is energized, valve V opens to a position to permit hydraulic fluid to enter the spinner head hydraulic cylinder 230 through the end 230b thereof which pushes the piston head forwardly in the cylinder to move the piston rod 235 and plate 237 and movable block 266 along the support bars 270 and 271. As this occurs, the spinning motor SM is started since 293 disengages 291 and permits limit switch 290 to close and supply electricity to SM. Since the rod R has dropped into the rod feed trough 160 adjacent the rollers 298 and 299, the forward movement of the plate 237 enables the spinner head roller 245 to contact and rotate and move the rod R. The contact by the roller 245 with the rod R at the desired angle induces a spinning rotation to such rod while at the same time moves the rod R in a forwardly direction so that it can pass through the cleaning and washing means 18 and into the thread forming machine 20.

The movable plate 237 is limited in its movement by the stop nuts 287 on the threaded bar 285 to prevent unwanted or unnecessary travel of the spinner head 245 and also to provide longitudinal stop or adjustment of the spinner head roller 245 relative to the rod R. This provides the correct contact pressure between 245 and rod R so that the roller will not bind against the rod and will contact it properly to spin it and move it forwardly.

As illustrated in FIG. 11, with the movable plate 237 positioned away from the rod R, the switch arm 291 contacts the shaft 293 extending from movable plate 237 and thereby opens limit switch 290 and shuts off the flow of electric current to the motor SM. As the plate 237 moves inwardly towards the rod R, the arm or contact 291 disengages from 293 and electric current flows to actuate the motor SM to rotate the spinner head 245.

At the end of the timing cycle, the timer 330 (FIG. 16) stops the flow of electricity to the solenoid 810, and this deactivates the solenoid 810 and allows the spring loaded valve V to move to a position to convey fluid through lines 232 and 233 to move the piston in cylinder 230 in an opposite direction to open or move the spinner head mechanism to its original position as shown in FIG. 11. When the plate 237 returns to the position as illustrated in FIG. 11, the rod 293 contacts 291 to disconnect switch 290 and the circuit to the motor SM which terminates rotation of the roller head 245.

The timer 330 can be set for any number of seconds, or period of time. It must be set so that the spinner head

245 will travel in and engage and rotate and move rod R until the rod enters the dies in the thread forming machine 20.

SECONDARY MAGAZINE

As illustrated in FIGS. 1, 3, 13, and 14, the secondary magazine of the present invention 10 is generally designated by the numeral 15. In FIG. 3, the magazine 15 includes a suitable base member 350 with pairs of vertical upstanding legs illustrated at 351 and 352 secured therewith. A support member 353 which includes a plurality of upstanding tabs 354 (only one of which is shown) is integrally formed or carried by legs 351 and 352. A secondary magazine base member 355 is pivotally secured by nut and bolt means 356 with the tab 354 such that if desired the nut and bolt means can be loosened and the secondary magazine base member 355 may be pivotally adjusted about the nut and bolt means 356 to change the angle of feed of the rods to the rod feed trough.

As illustrated in FIGS. 1, 13, and 14, rods R received from the elevator mechanisms generally designated at 14 (FIGS. 1 and 3) are received and roll on a plurality of cross member supports 357, each of which is secured with support members 358 in the form of angle iron pieces. Each of the cross support members 357 is suitably secured by any suitable means such as by welding to the secondary magazine base members 355 and the base members 355 are pivoted such that the cross members 357 are maintained at a suitable angle so that rods R transported by the elevators 14 to the cross members 357 will roll down and become stacked as illustrated in FIGS. 1, 3, 13 and 14. As illustrated in FIG. 1, the secondary magazine ejection means generally designated at 210 is spaced along the longitudinal length of the members 358 adjacent the suitable cross support members 357 which are nearest the rod feed trough.

As illustrated in more detail in FIGS. 13 and 14, each of the secondary magazine ejection means 210 includes a hydraulic cylinder 360 having a bracket means 361 secured with an end 360a thereof for pivotally connecting the cylinder 360 with an extension 362 mounted on the secondary magazine base member 355. The bracket 361 and extension 362 are connected together by pivot pin 363. A piston rod 365 extends outwardly from the end 360b of the cylinder 360 and is provided at its end with an attachment 366 for connection with a depending arm 367 of a collar 368 which is secured on longitudinally extending shaft 369 by set screws 370.

An arm 372 is provided with a collar (not shown) similar to collar 368 and which is held on shaft 369 by set screws (not shown). At the other end, arm 372 is provided with a slot 372a for receiving a pin 373. Pin 373 is mounted on an ejector blade 374, which blade includes a slanted upper surface 374a as illustrated in FIG. 14. A guide member 375 is mounted with the cross member 357 adjacent the upper portion thereof and envelops the sides of the ejector blade 374 to guide such ejector blade 374 during movement thereof. The pin 373 also extends through a slot 375a of the guide member 375 so that movement of the arm 372 upwardly will move the ejector blade 374 upwardly in the guide slot 375.

As illustrated in FIG. 13, the rods R contact the cross members 357 and roll downwardly on the inclined surface of the cross members 357. A stop member 380 prevents the rods R from rolling off the secondary magazine 15 into the rod feed trough 160. A secondary magazine guide member 381 having a curved upper surface 381a is secured with cross member 358 adjacent the rod feed trough 160 to insure that as the rods are ejected from the secondary magazine 15 that they will roll into the rod feed trough 160.

As explained hereinbelow, when the board 171 (FIG. 9) moves outwardly to its extreme position, the microswitch 206 is actuated which actuates a solenoid as will

be explained hereinbelow to actuate a valve which directs fluid to the cylinder 360. When fluid passes to one end of cylinder 360, a piston therein (not shown) moves piston rod 365 outwardly to pivot the arm 367. As the arm 367 pivots, the shaft 369 is rotated which causes the arm 372 connected thereon to move upwardly. Such upward movement of the arm 372 forces the ejector blade 374 upwardly to contact a rod R immediately adjacent the stop 380 and to thereby eject the rod R over the stop 380 and deposit such rod between the pairs of spaced rollers 166 and 167 of the rod feed trough 160, diagrammatically represented in FIGS. 13 and 14. The board 171 remains in the position diagrammatically shown in FIGS. 13 and 14 as long as limit switch 104 in the cleaning apparatus is open. When the rod R is deposited in the feed trough 160 and moves into the cleaning apparatus 18 and contacts wheel 18 to move it upwardly, the switch 104 closes and electric current is supplied to a solenoid which moves a valve to a position to conduct fluid to the other end of cylinder 193 to move the board 171 to the position of FIG. 9. The valve is spring loaded so that when the current is cut off the solenoid, the valve will move to enable fluid to flow to the opposite end of cylinder 193. When the board 171 moves, switch 206 is opened and fluid is conveyed to cylinder 360 to lower ejector blades 374 on the secondary magazine.

A primary microswitch means is generally designated at 385 and includes the wheel on microswitch plunger 386 extending into microswitch box 387 secured with the cross member 357. As illustrated in FIG. 14, with a rod R being ejected into the rod feed trough 160, the microswitch 385 is adjusted along rod 391 so that the last rod on the secondary magazine 15 depresses the wheel and plunger 386 and remains depressed until ejectors 447 on the primary magazine are lowered, as illustrated by the secondary ejectors 374 in FIG. 13.

When the ejectors 374 on the secondary magazine move down, as shown in FIG. 13, all the rods on the secondary magazine move forwardly. Such forward movement of the rods R releases the depressed plunger 386 to enable the plunger to move upwardly slightly above the surface of the cross members 357 (FIG. 13). Such upward movement of the plunger actuates the microswitch 385 which in turn actuates the primary ejection means generally designated at 390 (FIG. 1) to move the ejectors 447 upwardly and eject a rod from the primary magazine so that it can roll to the chamfering mechanism 13. Thereafter, as the chamfered rod is deposited on the secondary magazine, such rod contacts the plunger 386 to lower the plunger 386 below the surface of the cross member 357 and thereby close the switch to permit the ejectors on the primary magazine to lower so that the rods R on the primary magazine move against a stop 435. The primary ejector blades 447 when retracted are in position to eject a rod R when necessary.

It should be noted and as illustrated in FIGS. 13 and 14, the microswitch box 387 is adapted to be secured to a bar 391 so that the box 387 may be moved and adjusted along the longitudinal length of the cross member 357 as desired to accommodate the desired number of rods. The bar 391 is mounted adjacent cross member 357 by securing mounting members 392 to the cross member 357.

ELEVATOR ASSEMBLIES, ROD RACK, AND PRIMARY MAGAZINE

As illustrated in FIG. 1, an elevator motor means 400 is secured with the secondary magazine 15 adjacent one of the cross members 357 by any suitable means such as welding or the like. The motor means 400 rotates a continuous link chain 401 which is secured by a suitable sprocket (not shown) to drive a continuously rotatable shaft 402. The continuous rotatable shaft 402 is supported by bearing means (not shown) secured with extension members 403 of the cross members 357. Each of the plurality of elevators 14 includes an inverted channel

member 404 which is provided with bearings secured at its upper end 404a for mounting on shaft 402. Thus, the channel members 404 are pivotally mounted on shaft 402. A bracket support member 406 as illustrated in FIG. 3 is secured adjacent the other end 404b of the support member 404 and receives the arm 407. The arm 407 is pivotally supported adjacent one end on the secondary magazine base member 355 by a swivel block 408. The swivel block 408 has adjusting nuts 408a to permit rod 407 to be lengthened or shortened and thereby vary the angle of the elevator relative to the secondary magazine 15.

As illustrated in FIG. 15, each of the elevators 14 includes a sprocket 408 secured on the shaft 402, which sprocket 408 receives a continuous link chain 409. A rotatable shaft 410 (FIG. 3) is mounted by any suitable bearing means on the member 404 adjacent the lower end 404b of channel member 404 to enable the sprockets 411 (FIG. 15) to be mounted thereon.

As illustrated in FIG. 15, a pair of rod carrying members 413 and 414 is secured and mounted on each continuous link chain 409 at equal intervals therealong to elevate rods R from the chamfering mechanism 13 to the secondary magazine 15.

As illustrated in FIG. 15, a guide 415 is abutted adjacent an end 500a of a slanted cross member 500 of the chamfering mechanism 13 and extends outwardly toward the sprockets 411 to enable rods to roll from the chamfering mechanism 13 toward the elevators 14. The rods R are contacted by the carrying members 413 and 414 and are moved upwardly toward the cross members 357 of the secondary magazine.

As the rods approach the secondary magazine 15, they contact a curved member 418 which is curved on one end 418a such that the rods R will ride along the outer surface of the curved member 418 and then roll off the other end 418b of the curved member 418 onto the cross members 357 of the secondary magazine 355. The curved members 418 are in planes which are higher than the outer diameter of sprockets 408 and thus assure discharge of the rods R from the elevators before the carrying members 413 and 414 move around the sprockets.

As illustrated in FIG. 3, the rod rack 11 of the present invention 10 and primary magazine 12 have common base or support members 420. A plurality of pairs of vertical legs 421 and 422 (FIG. 3) extends upwardly from the base 420 and is secured with a longitudinal support member 423 and support member 424 which is a common support member for the rod rack 11 and primary magazine 12. A plurality of horizontal cross members 425 for supporting the rods R and cross members 426 is secured with the members 423 and 424. As illustrated in FIG. 3, the rod rack 11 receives a plurality of rods R which are stacked on the cross members 425 for movement of the stacked rods R onto the primary magazine 12.

As illustrated in FIG. 3, the primary magazine 12 includes a plurality of slanted braces 430 (only one of which is shown). A slanted rod receiving cross member 431 is secured by any suitable means such as welding to the slanted brace 430 adjacent one end thereof and is secured by any suitable means such as welding to the member 424 and leg 421 on the rod rack for receiving a plurality of rods R. A stop member 435 is secured to each of the slanted members 431 adjacent the end of the primary magazine 12.

The primary ejection means generally designated at 390 operates substantially by the same means and manner as the secondary ejection means 210 described hereinabove and includes a hydraulic cylinder 436 with a bracket 437 secured to its back end 436a, which bracket 437 is pivotally mounted by suitable means (not numbered) to leg member 421 in the same manner as the secondary ejection means 210 described hereinabove. A piston rod 440 extends outwardly from the front of the cylinder 436 and is secured by a suitable pivot means (not

numbered) to an arm 441 of a collar 442 rigidly secured with rotatable shaft 443, which shaft 443 extends parallel to and longitudinally of an angle beam 445 of the primary magazine 12. It is supported in suitable bearing and bracket (unnumbered) on braces 430. The rotatable shaft 443 is secured to each of collars 441 similarly to the shaft 369 and collars of the secondary ejection means 210.

A slotted arm 446 is secured by means of a collar (unnumbered) at one end with the shaft 443 and at the other end receives a pin (not numbered) in a slot (not numbered) of the arm 446. The pin is secured to a primary ejector blade 447 which is retained in a slotted guide member 448 in a manner similar to the secondary ejection means 210 explained hereinabove.

As previously described with regard to FIG. 13, when the rods R move downwardly along the cross members 57 to expose the wheel and plunger 386 to enable the wheel and plunger 386 of the microswitch 385 to move upwardly to actuate a solenoid, the solenoid moves a spring loaded valve to a position so that the primary magazine hydraulic cylinder 436 is supplied with fluid through a valve to move the piston in the cylinder 436 inwardly, which also thereby causes the piston rod 440 to move inwardly. Such movement of the piston rod 440 (FIG. 3) causes the arm 441 to rotate toward the cylinder 436 which rotates the shaft 443 and in turn moves the slotted arm 446 upwardly. As the arm 446 moves upwardly, this moves the primary magazine ejector blades 447 upwardly to eject a rod from the primary magazine onto slanted guide means 451 to convey it to the chamfering mechanism. The ejector blades 447 on the primary magazine will remain up as shown in FIGS. 3, 19, and 20 until the rod R is chamfered and conveyed to the secondary magazine 15. When the rod R rolls from the position shown in dotted line in FIG. 13 to the position shown in FIG. 14, the microswitch arm 385 is depressed which actuates the solenoid and the spring loaded valve connected therewith moves to a position to conduct fluid to the opposite end of cylinder 436 to retract primary ejector blades 447. This permits the rods R on the primary magazine to move against stop 435 and in position for the next ejection cycle. The stops 435 on the primary magazine and the stops 380 on the secondary magazine are adjustably supported on the primary magazine and secondary magazine, respectively, in any suitable manner so that they may be adjusted relative to the ejector blades and thereby accommodate different size rods.

As illustrated in FIGS. 3, 19, and 20, guide members 451 are slidably carried in block members 452a, which block members are pivotally supported on a rod 452 that extends adjacent the member 445. The rod 452 is in turn secured to 445 by suitable brackets 453 (FIG. 1). Thus, the guides 451 may be pivoted upwardly from contact with member 501 or the vice means 529 of the chamfering mechanism and may be moved along the rod 452.

CHAMFERING MECHANISM

As illustrated in FIG. 15, the chamfering head mechanism 13 includes a base member 470 for receiving two parallel I beam supports 471 and 472 for holding in position a plurality of rod racks generally designated at 473 positioned between the vice means 529. Each of the rod racks 473 is secured to each of the I beams 471 and 472 by a pair of parallel plates 474 and 475, one of which plates 475 is positioned adjacent the lower surface of the inner upper lips 476 of each of the I beams 471 and 472 and the other of which plates 474 is positioned on the upper surface of such lips 476. As illustrated in FIG. 15, the plates 474 and 475 are bolted together by suitable nut and bolt means 477. A pair of tubes 478 and 479 is secured by any suitable means such as bolts or the like to the upper surface 474a of the plate 474 adjacent one of each of the I beams 471 or 472 and each receives an elongated threaded bolt 480 and 481, respectively. A wheel 482 has a threaded sleeve which telescopes partially over each of the tube members 478 and 479 and threadededly engages with each of the elongated bolts 480 and 481, respectively. The wheels 482 may thus be rotated to extend and retract the upper ends of the bolts 480 and 481.

As illustrated in FIG. 15, each of the bolts 480 and 481 extends upwardly and is pivotally secured to the cross member 500 which is illustrated as being positioned such that the end 500a thereof is lower than the other end 500b of such member. An elevation member 510 is bolted at one end 510a with bolt means 511 to the upper surface of the cross member 500. The elevation member 510 extends upwardly to a point 512 and then slopes gradually down toward the end 500a and guide member 415. A suitable support block 514 is mounted between the member 510 and cross member 500 to keep the member 510 elevated from the cross member 500. As illustrated in FIG. 15, the members 451 extending from the rod 452 also contact one of each of the elevation members 510.

FIG. 15A is a diagrammatic view of a rod when supported on the racks 473 and engaged adjacent each end by vice means 529. More particularly, by referring to FIG. 1, it can be seen that at least three or four racks 473 are spaced longitudinally between the vice means 529. FIG. 15A shows that preferably the centermost racks 473 are elevated with respect to the racks 473 on each side thereof so that the central portion of rod R is bowed relative to the ends. This facilitates ejection of the rod from the vice means 529 of the chamfering mechanism as will be described in greater detail.

As illustrated in FIGS. 19 and 20, when a rod is ejected by the primary ejector blades 447 off the primary magazine 12, it rolls down the guide means 451 in the direction of the arrow 525 to contact a depressible lever 526. As the rod R rolls over the lever 526, it depresses microswitch plunger 527 to actuate a solenoid which in turn operates a valve to supply fluid to cylinder 528 to close the gripping means generally designated at 529. After the gripping or vice means 529 is closed, as shown in FIG. 20, a continuously rotatable chamfer head generally designated at 530 is moved inwardly to chamfer the end of the rod R. After the rod R is chamfered, the end of the rod R actuates a microswitch to cause the chamfer head 530 to move outwardly away from the end of the rod R as will be brought out hereinbelow. The actuation of the microswitch of the chamfer head 530 also then causes the gripping means 529 to release the rod R and enables the chamfer ejection means generally designated at 531 to eject the rod R onto a guide member 532, which guide member 532 is similar to guide member 415 abutted with the cross member 500 of the racks 473.

As illustrated in FIG. 1, a pair of the gripping means 529 is spaced longitudinally along the I beams 471 and 472 with one of the gripping means 529 being positioned adjacent the chamfer head 530 and the other gripping means 529 being spaced a suitable distance therefrom to receive the end portion of the rod R spaced from the chamfer head 530.

As illustrated in FIGS. 19, 20, and 25, the gripping means 529 spaced farthest from the chamfer head 530 is adjustable for movement parallel to the beams 471 and 472 so that the gripping means 529 may be adjusted to accommodate various lengths of the rods R. A rod 540 is positioned parallel to each of the beams 471 and 472 and is secured to its respective beam 471 and 472 by a longitudinally extending member 541 which is mounted on beams 471 and 472, respectively, in any suitable manner. A plurality of slideable block members 545 is each provided with an opening for sliding along the space bars 540, and the blocks 545 support a plate member 546 therebetween. There is a block member 545 at each corner of the plate 546, and each block is provided with a screw 540a to lock it against rod 540. Plate member 546 supports a pair of longitudinally extending block

members 547 and 548 which are secured by any suitable means such as welding or nut and bolt means with plate 546, which members 547 and 548 in turn support cross support members 549 and 550 on which is carried the movable gripping or vice means 529.

A gear track (FIGS. 1 and 25) 555 extends between beams 471 and 472 and is positioned between such beams by cross support members 576 (FIG. 25) secured transversely with each of the beams 471 and 472.

A gear 560 is positioned on a shaft 561a and intermeshes with the gears on gear track 555 such that rotation of the hand wheel 561, which is mounted on one end of shaft 561a, imparts rotation to the gear 560. The shaft 561a is mounted on plate 546 by suitable bearing means to accommodate rotation thereof. When the hand wheel 561 is rotated, plate 546 and the one gripping means 529 thereon are moved along gear rack 555.

As illustrated in FIGS. 18, 19, 20, 21, 25, and 26, the guide members 451 extend from the edge of the cross member 445 on the primary magazine 12 and terminate in an end 451a. Ears 490 (FIGS. 20 and 26) extend upwardly from and adjacent the end of cylinder 528 which keeps the guide means 451 extending to the vice means 529 aligned with movable vice 529 as well as the stationary vice 529. The member 600 is positioned in a parallel plane to the guide means 451 and is secured with the gripping means 529 to extend over a portion thereof as shown in FIG. 26.

In FIGS. 19 and 20, the gripping or vice means 529 closest to the chamfer head 530 is shown as being supported fixedly on blocks 541 and 542 on the beams 472 and 471, respectively. It is not mounted for movement and has microswitch 527 mounted on plate 606 which is positioned adjacent the cylinder end 528a and supports the microswitch 527.

As illustrated in FIG. 19, when the rod R is ejected from the primary magazine 13 by the primary magazine ejection blades 447, it rolls down guide means 451 and onto the member 600 and downwardly into the space 602 between the vice jaws. As the rod R is rolling down the plate 600, it depresses the lever 526 as brought out hereinabove.

A movable block 603 in each vice 529 has V-shaped jaws 603a (FIG. 23) thereon for gripping the rod R. A piston rod 604 extending from the piston in hydraulic cylinder 528 is connected to movable block 603 to move it and the jaws into gripping relation with rod R (FIG. 20). The hydraulic cylinders 528 for each vice are provided with hydraulic fluid through tubings 607 and 608 (FIG. 20) secured in each end 528b and 528a, respectively, of the cylinder 528.

Each vice means 529 is supported so that it may be adjusted and aligned with the chamfer head 530 before the whole operation begins. Each hydraulic cylinder 528 of each vice means 529 is carried on a cross bar 636 by suitable means engaging end 528a with the cross bar 636. Each vice head 631 of each vice means 529 is connected with a cross bar 630. Each cross bar 630 and 636 is provided with holes adjacent each end for receiving support rods 620 and 621 (FIG. 21). The ends of rods 620 and 621 are secured in cross members 614 and 615 (FIG. 20). The cross members 614 and 615 are connected to an supported on inclined cross bars 610 and 611, respectively, which in turn are mounted on and extend between 549 and 550. The cross blocks 614 and 615 at each end are supported by screw and bolt means designated generally at 612, thus providing an adjusting and securing arrangement at the four corners of the framework which supports each vice, the framework being defined by end cross members 614 and 615 and rods 620 and 621 connected therewith and which support the vice means 529. The rods 620 and 621 are parallel to each other and extend perpendicular to the cross members 614 and 615 in which they are supported. The members 614 and 615 extend transversely of members 549 and 550 upon which they

are adjustably carried. The cross bars 630 and 636 are provided with openings (FIG. 26) so that 630 and 636 may be moved along rods 620 and 621.

An adjustment screw 613 extends threaded through each cross bar 614 and 615 to abut the cross bars 636 and 615, respectively, to permit adjustment of each vice means 529 along its respective rods 520 and 521 and for holding it in a fixed alignment or relationship relative to the chamfer head 530.

FIG. 21A shows in greater detail the adjustment means 612 which permits independent elevation and lowering of each corner of the framework and enables the vice means 529 to be supported in a tilted position. A bolt 612a is threaded through 614 and 615 at each end and abuts the tilted plates 610 and 611. A countersunk bolt 612b fits through 614 and 615 at each end thereof and is threaded into plates 610 and 611, respectively. Thus, by adjusting 612a and 612b on each end of 614 and 615, the desired angle of tilt may be obtained.

Stationary vice jaw 631 is secured by bolts (not shown) to block 630a, and 630a is secured by bolts to each vice base 635 and to cross member 630 as shown in dotted line in FIG. 23. The vice jaw 631 has the configuration shown in FIG. 23 to aid in holding rods R and to aid in ejecting them from the vices after chipping.

As illustrated in FIGS. 19, 20, and 23, a pair of grip roller bars 640 is secured at one end 640a with the lower surface 603a' of the movable vice head 603 by suitable bolt means 641. A pair of roller brackets 640 extend downwardly through slotted openings 645 and 646 in the vice plate 635. A roller 648 is secured with one of each of the roller brackets 640. The brackets 640 are connected to each other by common pin 648a which also serves as an axle for each roller 648. Each roller 648 is flanged and its center part is adapted to roll on an upper surface 650a of a pair of spaced pivotal riding arms 652, only one of which is visible in FIG. 23. Spaced riding arms 652 (FIG. 21) are secured at one end by cross pin means 653. A tube 653a surrounds pin 653 between each arm 652 to maintain them in proper spaced relation. The spaced arms 652 are positioned relative to the vice plate 635 by a pivot pin 654 which also has a tube 654a between the arms, and the pin 654 extends between and connects the arms 652. The pin 654 is secured with a pair of spaced, depending supports 655 and 656, each of which is secured with vice plate 635 as shown in FIG. 23.

A pair of stationary pins 659 (FIG. 19) and 660 (FIG. 23) having heads 659a and 660a (FIG. 21) is secured to and hangs downwardly from the vice plate 635. As illustrated in FIG. 23, the bolt 660 is shown as threaded received at end 660b in vice plate 635. A pair of springs 661 and 662 encircles the bolts 659 and 660, respectively, and abuts at each upper end 663 to the lower surface 35a of the vice plate 635. A cross member 665 (FIG. 23) is movable up and down relative to each of the bolts 659 and 660 and extends therebetween. A pair of guide bushings 666 is secured to the plate 665 through which each bolt 659 and 660 extends. The other end 667 of each of the springs 661 and 662 abuts the cross bar 665.

The pair of pivotal arms 651 and 652 which are identical is each provided with slots 670 on one end 671 thereof for receiving a cross pin 672 therein which connects between the pair of ejector blades 673 and 674. This pin also serves to secure the slotted end 671 of one of the pivotal arms 652 with the ejector blade 673 and the other pivotal arm with ejector blade 674. The ejector blades 673 and 674 also serve as stop means when a rod is rolling toward the vice means 529 from the primary magazine, as will be described. As illustrated in FIG. 23, one end 675 of the ejector blades 673 and 674 is secured with the cross bar 665 with the other end 678 of the blades 674 adapted to extend upwardly through a pair of openings 679 and 680 (FIG. 22) for each blade 673 and 674, respectively, to eject a rod held between the

vice heads 603a and 631, respectively, and to stop a rod as it rolls from the primary magazine.

When the microswitch 527 (FIG. 19) is activated, a valve is moved to a position so that fluid is communicated through the tube 607 and into the cylinder 628 to push the piston rod 604 (FIG. 20) outwardly. This movement causes the vice head 603 to move outwardly so that the rod R is gripped between the vice jaws 603a and 631 as illustrated in FIG. 20.

As the vice jaws 603a and head 603 move forwardly, the roller brackets 640 connected therewith move in the slots 645 and 646 (FIG. 22) in the plate 635. Such movement causes the rollers 648 of each of the pivotal arms 640 to move down the surface 650a of the pivotal arms 652. As illustrated in FIG. 23, as the rollers approach the angle 685, the arm 652 is moved downwardly in the direction of the arrow 686 which causes the end 671 of the arm 652 to move downwardly. Such downward movement forces the cross pin 672 to move the ejector blades 673 and 674 downwardly which in turn moves the cross bar 665 downwardly on each of the bolts 659 and 660. The downward movement of cross bar 665 causes each of the coil springs 661 and 662 to uncoil as illustrated in FIGS. 20 and 21. Such downward movement lowers the ejector blades 673 and 674 to enable the stationary vice jaws 31 and movable jaws 603a to grip the rod R for subsequent chamfering with the chamfer head 530 as will be brought out hereinbelow.

After the rod R has been chamfered and the chamfer head 530 has moved away from the rod, the hydraulic flow is reversed to cause fluid to communicate through the hydraulic fluid tube 608 and the end 528a of the cylinder 528 to cause the movable vice head 600 to move away from stationary jaws 631. Such movement causes the rollers 648 to move back toward the connecting pin 653 secured with each of the pivotal arms 651 and 652 which thereby causes the arms 652 to move in the opposite direction of the arrow 686. Such movement causes the arms 652 to pivot about the cross pin 654 and to enable the slotted end 671 to contact the pin 672 to move the ejector blades 673 and 674 upwardly through their respective openings 679 and 680 to eject a chamfered rod R onto the guide means 532. The springs 661 and 662 normally tend to move ejectors 673 and 674 to their lowermost or retracted position.

As illustrated in FIGS. 18 and 21, the chamfer head 530 is mounted on cross members 700 and 701 secured to the beams 471 and 472. A support plate 702 is positioned between each of the cross members 700 and 701 and is secured with such cross members by any suitable means such as welding. A pair of rigid bars 704 is positioned parallel to the beams 471 and 472 and is mounted on plate 702 by longitudinally extending member 705 which connects rod or bar 704 to plate 702. A pair of slidable blocks 706 and 707 is secured with each of the parallel bars 704 and is adapted to slide along the longitudinal length of the spaced, parallel bars 704. A chamfer means hydraulic cylinder 710 is secured at one end 710a by a bracket 711 and pivotal pin 712 to a depending arm 713 mounted with the bearing case and bearing support 715 for the chamfer head. A piston shaft 716 extends outwardly from the other end 710b of the cylinder and is threadedly secured to a stationary member 720. A guard 721 is connected to beams 471 and 472 adjacent chamfer head 530, and when chamfer head 530 moves forwardly, the guard 721a encloses the stationary member 720 therein to keep chips from falling on the telescopes thereover to keep chips from the chamfering mechanism from falling on beams 471 and 472 and directs them to the floor. As illustrated in FIG. 18, the bearing case and support 715 is secured with motor supports 724 and 725, one of each of which is mounted with the pairs of blocks 706 and 707, respectively.

A motor driven gear reduction means 730a is mounted by a suitable base 730 to the bearing case and support 75

715. The drive shaft 731 has a sprocket which rotates a suitable continuous chain 732 for rotation of shaft 733 which continuously imparts rotation to a chamfer head member 740 through bearing case and support 715. Suitable holders (not shown) on the chamfer head member 740 support chamfer blades 741 which chamfer the ends of the rod R.

A rod 742 extends through 740 and 715 and is held at a predetermined relationship to blades 741 by a spring and bearing means (not shown). It also extends out the rear of 715 to be positioned adjacent a microswitch arm 743 of the microswitch 744. The bracket 751 is carried by motor support 725 and carries the extensions 752, upon which microswitch 744 is supported. The microswitch 744 can be positioned on 752 by a set screw at any desired position therealong.

When the movable vice jaw 603a is moved outwardly into the space 602 such that the rod R is gripped between the vice jaws 603a and 631 when each of the chamfer ejector blades 673 and 674 is lowered, the hydraulic cylinder 710 is then supplied with fluid to move the shaft 716 inwardly into the cylinder 710. Since the other end of the shaft 716 is secured with stationary member 720, such movement causes the pairs of blocks 706 and 707 on each of the bars 704 to move toward the adjacent gripping means 529. Of course, as the blocks are moved, the chamfer blades 741 are moved to contact the end of the gripped rod R (FIGS. 21 and 24). The continuous rotating blades chamfer the rod R along the surface 741a (FIG. 24) of the blades. As the chamfer blades 741 are pulled continuously toward rod R, the rod R contacts the end of member 742 to move it outwardly to contact the switch arm 743 which actuates a solenoid and valve arrangement to reverse the flow of fluid in the hydraulic cylinder 710 and thereafter the cylinders 528.

However, such reversal of flow first occurs in the hydraulic cylinder 710 which causes the shaft 716 to move outwardly and since the member 720 is stationary, such movement causes the pairs of blocks 706 and 707 to move away the stationary vice means 529 to thereby move the chamfering head 530 away from the rod R. Thereafter, the flow of the fluid in the cylinder valve 528 is reversed to cause the movable vice jaw 603a to move away from the rod R to enable the ejector blades 673 and 674 to eject the rod R from the space 602 between the vice heads 603 and 631, as will be described.

The primary magazine and rod rack may be fixed at a suitable vertical height. The chamfering means 13, secondary magazine 15, feed trough arrangement 16, and cleaning machine 18 may be provided with any suitable means (not shown) to adjust the vertical height in relation to each other and to the primary magazine.

OPERATION

As illustrated in FIG. 16, the hydraulic and electrical action of the invention 10 is combined schematically with the various mechanisms used and operated by the hydraulic cylinders and the like.

For the purposes of describing the operation of the invention, it will be assumed that a bundle of rods has been placed on the primary magazine, the bundle broken, and it is then desirable to load the secondary magazine with a suitable number of rods. As previously described herein, the microswitch 385 on the secondary magazine (FIGS. 13 and 14) is adjustable along the secondary magazine so that any desired number of rods, such as, for example, one to thirty, may be maintained on the secondary magazine. At this time, the ejectors 447 on the primary magazine are up, and the board 171, over feed trough 160, is swung open to the position of FIG. 14.

To move the rods from the primary magazine to the secondary magazine, the microswitch 385 in FIG. 16 as well as shown in FIGS. 13 and 14 is manually held down which opens switch 385, thereby de-energizing the solenoid 870 connected with a spring loaded valve 871, and

the valve moves to a position to supply fluid from supply line 873a through line 873 and cylinder 436 to move piston rod 410 (FIG. 3) outwardly, thus moving the ejectors 447 (FIGS. 19 and 20) to a retracted position which permits the rods to move against the stop 435 on the primary magazine. When the microswitch 385 is released, this causes the solenoid 870 to energize and move valve 871 to a position to supply fluid through 873a, 871, and 874 to move piston rod 440 inwardly and thereby cause the primary ejectors 447 to elevate to eject a rod R down towards the chamfering arrangement 530 (FIGS. 19 and 20). When fluid is supplied through line 874, fluid discharges from cylinder 436 and discharges through line 873 and valve exhaust 874b to the fluid reservoir (not shown). Similarly, when fluid is supplied through line 873 to cylinder 436, fluid exhausts therefrom through 874 through valve 871 and to 874b. After chamfering, the rod R is ejected from the vice means 529, as will be described, and moves up onto the secondary magazine, and the secondary magazine ejectors 374 are in an elevated position at this time (FIG. 14).

The operator again manually depresses microswitch 385 until the primary ejectors have moved downwardly. Thereafter, the switch 385 is released so the ejectors 447 move upwardly to eject a rod from the primary magazine and then the chamfering and elevating operation repeated until the desired number of rods has been placed on the secondary magazine. As this time, the last rod on the secondary magazine is in a position to hold the microswitch 385 depressed as shown in FIG. 14 so that the ejectors on the primary magazine in turn are retracted, as previously described, which allows the rods on the primary magazine to roll down against the block 435 to be in a position to be ejected the next time the microswitch 385 is uncovered by a rod.

The next step is to start the first rod through the cleaning apparatus by ejecting it into the feed trough 160. At this time, board 171 is in the open position of FIG. 14 and FIG. 16 so that electric current is maintained on the solenoid 857 and it is energized at this time so that switch 206 is closed. Referring again to FIG. 16 of the drawings, a suitable power source 900 is connected to supply electrical power to the electrical conduits 855 and 856. A button 901 is positioned at an accessible location as illustrated in FIG. 2 on one of the legs 151a, such bottom also being shown in FIG. 16. Also, the secondary magazine ejectors are elevated at this time, as shown in FIG. 14. To lower the secondary magazine ejectors 374, the button represented by the numeral 901 in FIG. 16 normally maintains the circuit represented by the electrical leads 855 and 856 to the solenoid 857 closed so that it is energized. When in this position, the solenoid acts to maintain valve 858 in a position to conduct fluid from a fluid power source (not shown) through the fluid supply line 861 through the valve 858 and through the line 860a to move the piston rod 365 (FIG. 14) inwardly to maintain the ejectors 374 in elevated position. However, when the circuit is broken by pushing the button 901, the solenoid is deactivated and the valve 858 is spring loaded so that it moves to another position, and fluid from the fluid supply line 861 is conducted through valve 858 to the line 861a on the other side of the piston in the cylinder 360. This moves the piston and discharges fluid from the cylinder through the line 860a and the discharge line 860 so that the secondary ejectors are lowered to the position shown in FIG. 13 of the drawings. During this cycle of operation, the board 171 maintains its outwardly spaced relationship relative to the feed trough as shown in FIG. 14.

As the rod R moves off the secondary magazine, it contacts and actuates the microswitch 320 (FIG. 11) which is connected with the electrical leads 800 and 801 which are connected with a suitable power source (not shown but represented by the numeral 802). The

electrical leads 800 and 801 are connected to the timer 330. The timer 330 has built therein a switch which closes when the timer is actuated by the actuation of switch 320 so that electrical current is supplied to the electrical conduits 811 and 812 to the solenoid 810. This energizes the solenoid 810 and moves the valve V on the spinning head mechanism to a position to receive fluid from the fluid supply conduit 814 from the fluid reservoir (not shown) and through the line 231 as represented by the arrow 815 to move the piston in the cylinder 230 and the piston rod 235 outwardly along with the spinner motor SM and spinner head 245 mounted on the plate 237. When the plate 237 moves, this also releases arm 290 so that the switch 820 is closed, thereby enabling electrical power to be supplied through the electrical conduits 821 and 822 to the spinning motor SM to rotate the spinner head 245.

The spinning motor SM and plate 237 on which it is mounted along with the spinner head 245 move inwardly to the dotted line position shown in FIG. 16 to engage the rod R and rotate it as well as longitudinally move it toward the cleaning apparatus represented generally by the numeral 18. The rod moves into the enclosure 25 (FIGS. 4, 5, and 6) to be received within the sleeves 25 (FIG. 8) and thereby contacts the wheel 83 and elevates it.

When the wheel moves up, the arm 831 pivotally connected therewith disengages the switch 84 so that it closes as shown in FIG. 16 diagrammatically so that the power from a power source (not shown) supplies current through the leads 840 and 841 to the solenoid 845 mounted with the spring loaded valve 846 on the secondary magazine. When this occurs, the solenoid is energized and thereby moves valve 846 to a position so that fluid from a fluid supply line 850 is conducted to the valve 846 and then through the line 847a to the end of the cylinder 193 and thereby moves the piston rod 192 outwardly, thus rotating collar 180 and bracket 201 depending therefrom outwardly to disengage from microswitch 206. The board 171 then is forced to the position shown in FIG. 9 of the drawings and illustrated in dotted line in FIG. 16 of the drawings and since the switch 206 has been opened, power to the solenoid 857 is cut off, thus permitting spring loaded valve 858 to move to a position so that fluid is supplied therethrough and from the fluid supply line 861 and through 861a to cylinder 360 and thus move the piston rod to retract the secondary ejectors 374. Fluid is discharged from the other side of the cylinder 360 through the line 860a and out the discharge line 860 back to the fluid power source.

As the rod R is ejected into the rod feed trough 160, it can be appreciated that the microswitch 385 on the secondary magazine is uncovered, and when this occurs, it moves up which closes the microswitch 385 and supplies current to the solenoid 870 via the electrical conduits 871a and 872. The solenoid 870 in turn opens the spring loaded valve 871 so that fluid passes through line 873a, valve 871, and then line 874 to force the piston in cylinder 436 inwardly in the cylinder to a position so that the piston rod 440 operates lever 441 and rotates rod 443 to actuate the arm 446 connected with the primary magazine ejectors 447 and thereby moves them up. This permits the ejectors 447 to move upwardly and eject a rod R over the stop 435 so that it moves down toward the chamfer mechanism designated generally by the numeral 13 in FIG. 3.

The wheel 83 rides on the surface of the rod, and when the end of the rod is reached, the wheel 83 falls and causes switch 84 to open the circuit, thus de-energizing solenoid 845. When this occurs, spring loaded valve 846 moves to a position so that fluid is conducted to the cylinder 193 and moves piston rod 192 into the cylinder, thus pivoting or swinging the board 171 to its open position. When it reaches its open position, depending arm 201 contacts microswitch 206, closing the circuit and

thereby energizing solenoid 857 and moves valve 858 to a position so that fluid is conducted to cylinder 360 to move ejectors 374 upwardly to eject a rod into feed trough 160. This in turn contacts switch 320 and starts the timer 330.

It is desirable to have a rod engaged by the thread forming dies at all times while they are in operation, and this arrangement accomplishes this since a rod is ejected into the rod feed trough 160, as a rod is about to leave the cleaning apparatus 18.

From the foregoing it can be appreciated that the cycle of operation can be continued until all of the rods R are conducted through the threader 20 illustrated in FIG. 2 of the drawings.

The chamfering mechanism is arranged so that the vices 529 engage a rod R prior to the time that chamfer head blades 741 engage the end of the rod and chamfers it. The vices 529 remain closed until the chamfer head blades 741 have been moved away from the rod R so that it can be ejected on the guides 532.

FIG. 17 is a diagrammatic and schematic illustration of the electrical and fluid circuit in relation to the vices and the chamfer head.

When the rod R rolls from the primary magazine towards the vice means represented at 529, it contacts the pivotally mounted lever 526 (FIG. 20) which actuates the plunger of switch 527 and closes the switch so that electrical power is supplied from a suitable power source (not shown) through the electrical leads 900 and 901 to the solenoid 903. The solenoid 903 is mounted on a four-way, detent valve 110, and when the solenoid is actuated, it moves the valve to a position so that fluid from a suitable fluid supply source (not shown) may flow through line 904 and through valve 110 to line 905. The fluid flows through 905, through line 906 and into the cylinder designated 528 so that the vice head 603 and jaws 603a move forwardly when the piston 604 moves them forwardly towards the ejectors 673 and 674. Simultaneously, the arm 640 moves the rollers 648 along arms 651 and 652, thereby retracting ejectors 673 and 674 as the vice jaws move towards stationary vice jaw 631, and thus a rod R is clamped between the vice jaws ready for chamfering. As the piston in cylinder 528 moves, the pressure in the hydraulic system drops slightly and when the piston in the cylinder 528 reaches its maximum stroke, the pressure in the hydraulic system will return to its normal pressure, say, if it is set at 100 pounds per square inch, it will return to this pressure, and this pressure will react back through line 906 and 905 and through line 910 and through line 911a into cylinder 911b, thereby opening sequence valve 911. This allows fluid to flow through line 912 and into cylinder 710 mounted with the chamfering head, and the cylinder 710 moves to the left as viewed in FIG. 17 since its piston 710c is secured by rod 716 to the member 720. As this occurs, the chamfering mechanism 530 moves as represented by the arrow 916 to engage the end of the rod R.

As previously described, the switch housing 745a is adjustable to determine the amount of chamfer on the end of the rod R, and when the end of the rod 742 projecting from the chamfer head 741 is engaged by the end of the rod R and contacts the switch arm 743, it closes the circuit so that current may flow through the lines 921 and 922 to the solenoid 920 on the four-way valve 110. This causes the valve to be moved in the opposite direction so that fluid may then flow from the intake 904 to be discharged through 918 and then through 923 to the opposite end of cylinder 710 to first back the chamfer head blades 741 away from the rod R. When the piston 710c has reached its limit of travel in cylinder 710, this builds the pressure up in 710 and this back pressure is fed through line 923 and then into lines 930 and 931b and then to cylinder 931a which opens the sequence valve 931, and allows fluid to flow through 933 into the opposite end of cylinder 528 connected with the

vice means 529 as previously described. This opens the vice means 529 and simultaneously raises the ejector blades 673 and 674. On the next stroke of the piston in cylinder 528, the fluid will go through line 933 and then through check valve 935 to the four-way valve 110 previously mentioned and to exhaust through line 904a to the fluid reservoir.

It can be appreciated similarly that when the fluid is exhausted from the cylinder 710 by reason of the chamfer head moving backwardly, the fluid is exhausted through line 912 back through check valve 910b and through line 910, line 905, and out discharge line 904a into the fluid reservoir.

Attention is directed to FIG. 27 wherein an adjustment arrangement on the primary magazine and bundle rack is shown which is a sectional view in perspective along the line 27—27 of FIG. 1 to permit the rods to be adjusted so that they can be aligned with the remainder of the mechanism. Such arrangement includes bolts 1000 which fit through the upstanding brace 1001 at spaced intervals along the edge of the primary magazine. Nuts 1002 and 1003 thereon on each side of the brace 1001 are provided to hold 1005a in a predetermined position. The heads 1004 of the bolts 1000 are secured to the angle iron 1005, and it can be appreciated that this may be moved in and out on the base 1006 which is integrally connected by any suitable means such as bolts or welding or the like to the vertical extending brace 1001. The ends of the rods on the primary magazine and bundle rods abut the portion 1005a of the angle iron and thereby permit alignment thereof with the balance of the invention. On the bundle rack, the portion 1001 and 1005a may be two or three times higher to abut a bundle when it is abutted thereagainst.

35 In FIG. 28, an enlarged view showing the adjustment of the rod feed trough 160 is shown wherein bolts 160d are secured through an upstanding portion of each of the legs and abut against trough sides 162 and 163. The trough bottom 161 is adapted to be engaged by bolt 160d which is similar to the other bolts for holding the rod feed trough 160 in the proper relationship with the washing and cleaning apparatus and the secondary magazine.

The rollers 167 previously described are arranged in staggered relationship in the sides 162 and 163 of the rod feed trough for supporting the rod R.

45 The foregoing disclosure and description of the invention are illustrative and explanatory thereof, and various changes in the size, shape, and materials as well as in the details of the illustrated construction may be made within the scope of the appended claims without departing from the spirit of the invention.

I claim:

1. A method of handling, preparing, and feeding rods to a thread forming machine comprising the steps of:
  - (a) placing the rods to be threaded on a first support structure in side by side relation;
  - (b) gripping each rod and holding it while cutting at least one end thereof to form a chamfer thereon;
  - (c) moving the rod to a second support structure adjacent a rod feed trough;
  - (d) positioning the rods one at a time in the rod feed trough;
  - (e) supporting the rods adjacent one end of the feed trough between adjustable rollers;
  - (f) rotating the rod and moving it longitudinally out of the rod feed trough through the rollers toward a cleaning apparatus;
  - (g) cleaning the rod with solvent in the cleaning apparatus while the rod is rotating and moving therethrough; and
  - (h) feeding the cleaned rod directly into a thread forming machine while the rod is rotated.

2. The method of claim 1 including the step of feeding another rod into the cleaning apparatus at a predetermined time whereby a rod is always engaged by the thread forming machine.

3. The method of claim 1 wherein the cutters which engage the rod end for chamfering are first disengaged therefrom before the gripped rod is released.

4. The method of claim 1 including the step of supplying another rod from the first support structure, then through the chamfering step and then to the second support structure when a rod is removed from the second support structure into the rod feed trough.

5. An apparatus for handling, preparing, and feeding rods for a thread forming machine comprising:

- (a) a primary magazine for supporting a plurality of stacked rods;
- (b) means for engaging at least one end of each rod and chamfering it;
- (c) a secondary magazine for receiving the chamfered rods;
- (d) means for conveying the chamfered rods to said secondary magazine;
- (e) a rod feed trough extending longitudinally adjacent said secondary magazine;
- (f) means for ejecting said rods from said secondary magazine into said rod feed trough one at a time;
- (g) a cleaning apparatus aligned with said rod feed trough for receiving a rod from the trough and cleaning it;
- (h) support rollers for each rod adjustably mounted between said cleaning apparatus and rod feed trough; and
- (i) means for engaging and rotating said rod and moving it longitudinally out of said rod feed trough and into said cleaning apparatus.

6. The invention of claim 5 wherein said engaging and rotating means includes a timing mechanism to maintain rotation of said rod until it passes through said cleaning apparatus and is received by the thread forming machine.

7. The invention of claim 6 wherein contact means contacts said rod as it travels along said rod feed trough and cleaning apparatus, there being switch means which is affected when said contact means no longer contacts a rod to actuate ejection means adjacent said secondary magazine and eject another rod into the rod feed trough.

8. An apparatus for handling, preparing, and feeding rods for a thread forming machine comprising:

- (a) a primary magazine for holding a plurality of stacked rods in side by side relation;
- (b) primary magazine ejection means for ejecting rods from said primary magazine one at a time;
- (c) a chamfering mechanism for chamfering at least one end of each rod;
- (d) chamfer ejection means for ejecting the rod from said chamfering mechanism;
- (e) elevator carrying means for moving the chamfered rod from said chamfering mechanism;
- (f) a secondary magazine for receiving the chamfered rod from said elevator carrying means;
- (g) secondary magazine ejection means for ejecting the chamfered rod from said secondary magazine one at a time;
- (h) a rod feed trough for receiving the chamfered rod when it is ejected from said secondary magazine;
- (i) support roller means for said rod mounted adjacent one end of said rod feed trough, said support rollers being adjustable relative to said rod feed trough;
- (j) a spinning mechanism for spinning and moving the rod forwardly in said feed trough toward the thread forming machine; and
- (k) a cleaning apparatus between said rod feed trough and thread forming machine for cleaning each rod immediately before entry thereof in the thread forming machine.

9. The structure as set forth in claim 8 comprising a movement dampening means adjacent said feed trough for limiting unwanted movement of the rod as it moves and spins in said rod feed trough to said cleaning apparatus.

10. The structure as set forth in claim 9 including:

- (a) a timer means;

(b) a switch means electrically connected to said timer means, said switch means actuating said timer when a rod is ejected from said secondary magazine into said rod feed trough; and

(c) said spinning mechanism including a spinner head and motor means to rotate said spinner head, said mechanism being responsive to actuation of said timer means to effect movement of said spinner head toward and away from the rod in said rod feed trough, and wherein movement of said spinner head toward said trough initiates rotation of said motor connected therewith so that when said spinner head contacts the rod in said rod feed trough, the rod is rotated and moved along said rod feed trough, through said cleaning means, and into the thread forming machine.

11. The structure as set forth in claim 10 wherein said spinning mechanism includes:

- (a) means for adjusting it about an axis transverse to the rod feed trough to adjust the angle of contact of said spinner head with said rod depending upon the size rod; and
- (b) additional means to vary the travel of said spinning mechanism toward and away from the rod.

12. The structure as set forth in claim 11 including:

- (a) switch means positioned in the cleaning apparatus;
- (b) means mounted in said cleaning apparatus for contacting the surface of the rod as it moves therethrough, said means disengaging from said rod surface when the end of a rod passes therebeneath to affect said switch means;
- (c) a solenoid electrically connected with said switch means;
- (d) a spring loaded valve means connected with said solenoid to control fluid flow through said valve;
- (e) a double acting hydraulic cylinder with piston means therein, said cylinder being connected by conduits to said valve means;
- (f) a piston rod connected with the piston in said cylinder and connected to said movement dampening means to move said movement dampening means to a position adjacent said rod feed trough for limiting movement of a rod when said contact means in said cleaning apparatus is in contact with a rod and for rotating said movement dampening means away from said rod feed trough for receiving another rod therein when the end of a rod passes beneath said contact means;
- (g) means connected with said piston rod and said rod dampening means;
- (h) switch means mounted to be engaged by said means which is connected with said piston rod and movement dampening means to close said switch;
- (i) a solenoid electrically connected with said last named switch means;
- (j) spring loaded valve means connected with said solenoid to control the flow of fluid therethrough;
- (k) a double acting cylinder having a piston therein and fluid flow conduits connected with said last named valve means; and
- (l) a piston rod connected with the piston in said cylinder means and engaged with said secondary magazine ejection means so that when said switch means is closed by movement of said movement dampening means, said secondary magazine ejection means are actuated to elevate and eject a rod into the feed trough while said movement dampening means is positioned outwardly.

13. The structure as set forth in claim 12 wherein when said rod is moved forwardly into the cleaning apparatus, it contacts said rod surface contact means which affects said switch means in said cleaning apparatus and thereby actuates said valve means which flows fluid to

75 the cylinder means having a piston therein with said pis-

ton rod connected to said movement dampening means to thereupon move said movement dampening means to a position over the rod feed trough to inhibit unwanted movement of the rod.

14. The invention of claim 13 including:

- (a) switch means on said secondary magazine positioned at a predetermined position thereon to accommodate a desired number of rods in side by side relation on said secondary magazine, said switch means being affected by ejection of a rod into said rod feed trough by said ejection means on said secondary magazine;
- (b) a solenoid electrically connected with said switch means;
- (c) a spring loaded valve means connected with said solenoid;
- (d) a double acting cylinder having a piston therein and fluid flow conduits connected with said valve means; and
- (e) a piston rod connected with said ejection means on the primary magazine for raising said primary magazine ejection means and ejecting a rod from said primary magazine when said switch means on said secondary means is uncovered, said primary magazine remaining elevated until said rod has been chamfered and elevated to said secondary magazine to cover said switch means positioned thereon, whereupon said valve means conducts fluid to the other end of said cylinder means connected with said primary magazine ejection means to lower said primary magazine ejection means.

15. The structure as set forth in claim 14 including:

- (a) guide means for guiding the movement of rods ejected from said primary magazine onto said chamfering mechanism;
- (b) switch means mounted adjacent said guide means, said switch means being actuated by movement of a rod ejected from said primary magazine over said guide means;
- (c) said chamfering mechanism including:
  - (1) a rotatable chamfer head for chamfering at least one end of the rods which is inserted into the thread forming machine;
  - (2) support means for receiving the rod from said guide means; and
  - (3) gripping means for gripping the rod as it is chamfered.

16. The invention of claim 15 including:

- (a) solenoid means connected with said switch means mounted adjacent guide means;
- (b) sequence valve means connected with said solenoid means for controlling flow of fluid to said gripping means to cause them to grip the rod while it is being chamfered, for releasing the gripping means after the chamfering of the rod, and for conducting fluid to a hydraulic cylinder for moving said chamfering means into engagement with the end of said rods;
- (c) said solenoid actuated sequence valve having flow conduits arranged to first conduct fluid to said cylinders which have pistons therein and a piston rod connected with said gripping means for first closing said gripping means on said rod prior to conducting the fluid to the hydraulic cylinder which affects movement of said chamfering means for chamfering of said rod; and
- (d) said solenoid operated sequence valve having fluid conduits arranged so that after said rod has been chamfered, said chamfering mechanism will be first disengaged from the end of the rod prior to the time that fluid is conducted to said cylinder means associated with said gripping means for releasing said gripping means.

17. The structure as set forth in claim 16 wherein said secondary magazine is slanted toward said feed trough and wherein a plurality of chamfered rods positioned

thereon in side by side relation moves downwardly toward said feed trough as successive rods are ejected and positioned in said feed trough.

18. The invention of claim 15 including said support means which receives the rod and supports it while engaged with the gripping means for chamfering being adjustable vertically so that the supports intermediate said vice means may be elevated to affect a bow in said rod.

19. The invention of claim 18 including ejection means associated with said gripping means and movable toward retracted position upon movement of said gripping means toward closed position, and said ejection means movable upwardly to eject a rod from said gripping means as said gripping means moves away from engagement with said rod.

20. The structure as set forth in claim 19 wherein said elevator carrying means includes:

- (a) a pair of spaced carriers extending from adjacent said chamfer ejection means to said secondary magazine;
- (b) each of said spaced carriers including:
  - (1) a pair of spaced continuously rotatable sprocket means;
  - (2) a continuous link means secured with each of said sprocket means; and
  - (3) rod carrier means secured with said continuous link for carrying the rod from said chamfer mechanism to said secondary magazine.

21. The invention of claim 5 wherein said cleaning apparatus includes:

- (a) a housing;
- (b) wire brushes rotatably mounted within said housing and spaced for contacting a rod as it travels therebetween; and
- (c) means for imparting rotation to said brushes.

22. The invention of claim 21 including adjustable support means for said brushes to vary the spacing therebetween to accommodate various size rods.

23. The invention of claim 22 including a spring loaded arrangement on said means for imparting rotation to said brushes whereby said means will impart rotation to said brushes at various adjusted spacings.

24. The invention of claim 21 including a separate enclosure for said brushes to separate them from the remainder of said cleaning enclosure.

25. The invention of claim 24 including:

- (a) means forming a container for a solvent bath in said enclosure;
- (b) means for conveying said solvent to spray on said rotating brushes adjacent the rod passage space;
- (c) means for conducting the solvent from said separate enclosure after it has been sprayed on said brushes to said container; and
- (d) means for jetting air on said rod as it exits said cleaning enclosure to aid in removing solvent therefrom and returning it to said solvent container.

26. A method of moving and preparing rods for threading with a thread forming machine comprising the steps of:

- (a) sequentially moving a spinner head inwardly by hydraulic means to contact a rod positioned in a rod feed trough adjacent the thread forming machine;
- (b) spinning the rod forwardly toward the thread forming machine with the spinner head;
- (c) cleaning the rod before entry into the thread forming machine;
- (d) sequentially actuating a dampening movement board for enabling the board to move outwardly;
- (e) sequentially ejecting an adjacent rod from a secondary magazine into the rod feed trough;
- (f) sequentially moving the board inwardly to prevent unwanted movement of the rod deposited in the feed trough;
- (g) sequentially moving rods on the secondary magazine toward the feed trough, such movement being

- caused by sequentially ejecting rods from the secondary magazine into the feed trough;
- (h) sequentially ejecting rods from a primary magazine onto a chamfering mechanism, such sequential ejection being caused by movement of the rods on the secondary magazine;
- (i) sequentially chamfering the rods ejected onto the chamfering mechanism; and
- (j) sequentially moving the chamfered rods from the chamfering mechanism to the secondary magazine for ejection into the feed trough wherein the rods are sequentially inserted into the thread forming machine by the spinning head.

27. The steps as set forth in claim 26 including the steps of:

- (a) sequentially actuating a timer for controlling movement of the spinner head; and
- (b) actuating the timer by ejecting rods from the secondary magazine into the rod feed trough.

28. The steps as set forth in claim 26 wherein the step of sequentially chamfering the rods includes the steps of:

- (a) sequentially tripping a chamfer means switch by ejecting rods from the primary magazine onto the chamfer mechanism;
- (b) sequentially closing a gripping means to grip the rods by tripping the chamfer means switch;

- (c) sequentially moving a continuous rotatable chamfer head inwardly to chamfer the gripped rod;
- (d) sequentially actuating a switch in the chamfer head with the rod;
- (e) sequentially moving the chamfer head outwardly by the actuation of the chamfer head switch;
- (f) sequentially opening the gripping means to release the rod; and
- (g) sequentially ejecting the chamfered rod from the gripping means.
